UNITED STATES PATENT OFFICE.

CHARLES W. SMITH, OF DETROIT, MICHIGAN.

DESIGN FOR A WHIP-TOP.

SPECIFICATION forming part of Design No. 32,971, dated July 17, 1900.

Application filed May 23, 1900. Serial No. 17,761. Term of patent 7 years.

To all whom it may concern:

Be it known that I, CHARLES W. SMITH, a citizen of the United States, and a resident of the city of Detroit, county of Wayne, and State of Michigan, have invented and produced a new and original Design for Whip-Tops, of which the following is a specification, reference being had to the accompanying drawings, forming part thereof.

Figure 1 is a perspective view, and Fig. 2 is a plan view, of the top.

As shown in the drawings, the leading or material feature of my design consists of the round thin disk-shaped upper part, the inverted-cone-shaped lower part, and the con-

necting part between the upper and lower parts, having the appearance of a pillar supporting the top from the lower end.

Having described my invention, what I claim as new, and desire to secure by Letters Patent, is—

The design for a whip-top as herein shown and described.

In testimony whereof I sign this specification in the presence of two witnesses.

CHARLES W. SMITH.

Witnesses:

S. E. THOMAS,
IRENE GILBERT.
